Primary Examiner — Keith J Wilson(74) *Attorney, Agent, or Firm* — Cahn & Samuels, LLP(57) **CLAIM**

The ornamental design for a static mixer, as shown and described.

DESCRIPTION

FIG. 1 illustrates a front perspective view of a static mixer. FIG. 2 illustrates a rear perspective view of the static mixer of FIG. 1.

FIG. 3 illustrates a front view of the static mixer of FIG. 1. FIG. 4 illustrates a cross-sectional view of the static mixer of FIG. 1 along the cut depicted in FIG. 3.

FIG. 5 illustrates a rear view of the static mixer of FIG. 1; and,

FIG. 6 illustrates a side view of the static mixer of FIG. 1 which is the same when viewed from any side.

1 Claim, 3 Drawing Sheets(56)
